UNITED STATES PATENT OFFICE.

BENGT M. W. HANSON, OF HARTFORD, CONNECTICUT, ASSIGNOR TO PRATT & WHITNEY COMPANY, OF NEW YORK, N. Y., A CORPORATION OF NEW JERSEY.

CONTOUR-GRINDING MACHINE.

1,367,382.

Specification of Letters Patent.

Patented Feb. 1, 1921.

Application filed July 31, 1918. Serial No. 247,631.

To all whom it may concern:

Be it known that I, BENGT M. W. HANSON, a citizen of the United States, residing at Hartford, in the county of Hartford and 5 State of Connecticut, have invented certain new and useful Improvements in Contour-Grinding Machines, of which the following is a specification.

This invention relates to grinding machines of the type set forth in my copending 10 application for metal reducing machines, Serial No. 102,458, filed June 8th, 1916.

One of the objects of the invention is to provide, in a machine of this type, means 15 whereby a non-radial relief may be given to the teeth of a cutter having parts of its contour sharply inclined with respect to the axis. This is accomplished by angularly adjusting the grinding wheel. A further 20 object of the invention is to provide certain improved details of construction which increase the accuracy of the machine and enable it to be operated more conveniently and rapidly. These several objects of the invention will be more fully apparent from the 25 following specification.

The accompanying drawings show the embodiment of the invention which I now deem preferable, but it will be understood that 30 numerous changes may be made without departing from the spirit of the invention as set forth in the claims appended to this specification.

Of the drawings:

35 Figure 1 is a front elevation of the machine, certain of the parts being shown in section.

Fig. 2 is a side elevation of the machine, certain of the parts being shown in section 40 and other parts being broken away.

Fig. 3 is a plan view.

Fig. 4 is a plan view showing the controlling linkage for the wheel and wheel support.

45 Fig. 5 is a fragmentary view illustrating the operative relationship between the grinding wheel and the cutter.

Fig. 6 is a fragmentary view showing the wheel and the cutter in another position of 50 relative adjustment.

Fig. 7 is a plan view showing the parts appearing in Fig. 5. In this view the wheel and the supporting parts therefor are shown as having been angularly adjusted.

55 Fig. 8 is a view similar to Fig. 7 but

showing the wheel and the supporting parts therefor in another position of angular adjustment.

Fig. 9 is a fragmentary view showing the indexing stop in a different position of adjustment from that shown in Fig. 1. 60

Fig. 10 is a side view somewhat similar to Fig. 2 but showing the wheel dressing mechanism in operative position.

Fig. 11 is a fragmentary plan view somewhat similar to Fig. 3 but showing the wheel dressing mechanism in operative position. 65

Fig. 12 is a fragmentary front elevation somewhat similar to Fig. 1 but showing the wheel dressing mechanism in operative position. 70

Fig. 13 is a fragmentary vertical sectional view showing the device for connecting the wheel dressing mechanism with the wheel 75 support.

Fig. 14 is a view showing a gage for adjusting the wheel dressing tool for wheels of different thicknesses.

Fig. 15 is a diagrammatic view showing 80 the movement which the wheel dressing tool must have when the point thereof is eccentric.

Fig. 16 is a view illustrating the adjustment of the operating handle to provide the 85 change of position indicated in Fig. 15.

Fig. 17 is a horizontal sectional view showing the eccentric sleeve for adjusting the wheel dressing tool.

Referring to the drawings, 1 represents 90 the main frame of the machine which is or may be mounted upon a base or pedestal 2 of any desired construction. As more clearly appears in Fig. 4, the frame 1 is in the form of a hollow box or housing within which are 95 mounted the devices for supporting and controlling the movement of the grinding wheel. These supporting and controlling devices are adapted to permit the wheel to move horizontally in any direction, but they hold 100 it in parallelism while being so moved. Preferably I provide a pantographic mechanism as will be described.

Extending across the top of the frame is a tie plate 3. Interposed between the tie 105 plate 3 and the bottom of the frame is a bearing member 4 which is provided with two sets of vertical pivots engaging two parallel links 5 and 6. These links extend beneath the tie plate and are pivoted to a 110

cruciform member 7 which is thus mounted for movement forward and backward in parallelism. The cruciform member 7 is provided with two sets of vertical pivots 5 which engage parallel links 8 and 9. These links extend forward through openings in the frame and at their forward ends are pivotally connected with a plate 10. By means of the pantographic connections 10 which have been described the plate 10 is freely movable horizontally in any direction, but is nevertheless always maintained in parallelism. The grinding wheel is carried by the plate 10 by means of devices to 15 be described and is thus bodily movable with respect to the cutter or other part to be ground.

Hinged to the main frame 1 at 11 is a bed plate 12. This plate 12 together with 20 the devices carried thereby can be swung upward about the hinge axis to expose the linkage and other parts contained within the housing 1. To the plate 12 are secured the devices which support the cutter or other 25 part to be ground.

The machine is primarily adapted for grinding cutters with irregular or "formed" contours such as are used in milling machines, and therefore in referring to the 30 work holding parts I will principally confine myself to a description of the elements necessary for holding such a milling cutter. For holding the shank of the cutter to be ground, or for holding an arbor on which 35 the cutter is mounted, I provide a work spindle 13 which is rotatable in a bearing 14. As illustrated, there is a cutter A mounted on an arbor B. The spindle can be turned by means of a knurled knob 15 and 40 the spindle can be locked in any desired position by means of the clamping screw controlled by a hand lever 16.

In grinding a toothed cutter it is usually necessary to index the cutter in order that 45 the teeth thereof may be successively presented in proper relation to the grinding wheel. To assist in indexing, I preferably provide a stop mechanism adapted to directly engage the front surfaces of the teeth. 50 As illustrated, this mechanism comprises a stop finger 17 carried by a series of rods 18, 19 and 20 which are adjustably connected and which can be secured in any desired relative positions by means of clamping 55 screws. The rod 20 is carried by the bearing 14 and can be clamped by means of the clamping screw 21. It will be seen that by means of these several rods the stop 17 is universally adjustable.

60 Preferably the bearing 14 is carried by a slide 22 which is movable forward and backward under the control of a screw operated by a hand wheel 23. Preferably the wheel is provided with graduations, as shown in 65 Fig. 3, whereby the operator, by making

use of a pointer 24, can determine the position or the extent of movement of the slide and of the spindle.

The slide 22 is mounted on a second slide 25 which is movable transversely on ways carried by the plate 12. For moving the slide 25 there is provided a screw operated by a hand wheel 26. Preferably adjustable stops are provided for limiting the movement of the slide 25. As illustrated, these 70 stops are in the form of lock nuts 27 and 28 engaging a rod 29. The rod 29 is adjustable longitudinally but can be clamped in any desired position of adjustment by means of a screw 30. Between the nuts 27 and 28 the rod 29 extends through an aperture in a lug 31 carried by the slide 25, and the nuts by engaging this lug serve to limit the movement of the slide.

Preferably I provide an outboard or tail-stock bearing which can be used to support the end of the arbor B when such an arbor is used. This bearing is in the form of a bushing 32, the central aperture of which fits the arbor. The bushing is mounted in 90 a bracket 33 and can be held in any desired manner. By means of a bolt 34 the bracket 33 is adjustably secured to a slide 35 which is movable forward and backward on the plate 12. The slide can be held in any position of adjustment by means of a bolt 36 engaging a T-slot in the plate.

As I have already stated, the grinding wheel is carried by the plate 10. In accordance with my present invention, there is a 100 grinding wheel supporting bracket 37 which is vertically pivoted to the plate by means of a pivot pin 38. The upper part of the bracket is provided with vertical ways along which is movable a slide 39. This slide is 105 controlled by a non-rotatable screw 40 which is movable vertically by means of the nut 41. The slide can be clamped in adjusted position by means of a nut 42 engaging a suitable screw. As is most clearly shown in 110 Fig. 3, the slide 39 is provided with aligned horizontal bearings 43 and 44 in which is mounted a spindle 45. For rotating the spindle there is provided a belt wheel 46. A grinding wheel 47 is mounted on the spindle 115 45 but is readily detachable so that another wheel can be substituted when required.

As already stated, the bracket 37 is pivotally connected with the plate 10. In order 120 that the bracket may be locked in any desired position of angular adjustment, there is provided a rod 48 pivoted to the plate 10 at 49. The bracket 37 is provided with two ears 50 between which there is mounted a 125 yoke 51 which engages the rod 48. By means of a bolt 52 the yoke can be clamped against the rod so as to lock the bracket 37 and the associated parts in any desired position.

Because of the pantographic linkage which supports the plate 10, this plate together with the bracket and other associated parts are movable freely in any direction but are maintained in parallelism. In order that the operator may conveniently move these parts transversely, I provide a sliding rack bar 53 which is suitably guided on the frame 1. This bar is connected with 10 the plate 10 by means of a link 54. A shaft 55 is mounted in a bearing 56 carried by the frame 1, and mounted on this shaft is a pinion 57 which meshes with the rack 53. A hand lever 58 is secured to the shaft 55 15 for turning it. In this way the bar 53 can be moved longitudinally carrying with it the plate 10 and all connected parts. It is sometimes desirable to disconnect the pinion 57 from the rack, and this can be done by 20 pushing inward on the hand lever, thus carrying the pinion to the position indicated by dotted lines in Fig. 2. A spring-pressed plunger 59 engaging a groove 60 in the shaft 55 normally serves to hold the pinion 25 in its operative position.

As shown in Figs. 3 and 4 the tie plate 3 is extended at the front of the machine and is provided with notches adapted to receive projections 61, 61 on a former plate 30 62 which is used to guide the plate 10 and associated parts as they are moved transversely by means of the hand lever 58. The former is preferably constructed in two sections, there being an auxiliary part 63 which 35 is detachable and which is shaped at its edge to conform to the contour of the cutter to be ground. Occasionally, however, the auxiliary part 63 is not large enough, and in that case a one-piece former is provided 40 having its entire edge shaped as required. For securing the former there is provided a clamping plate 64 and a clamping screw 65 which extends through a notch 66 in the former.

45 The bracket 37 carries a former stud 67 which is adapted to engage and coöperate with the former 62. For securing the former stud 67 there is provided on the bracket 37 a hollow boss 68 through which 50 extends a slotted bolt 69. The bolt extends entirely through the bracket and at the end opposite to the slot is provided with a nut 70. The former stud 67 has an enlarged shank 71 which extends through the slot in 55 the bolt 69 and which engages the end of the boss 68 or engages a washer 72 which is interposed. It will be clear that when the former stud has been put in place, as shown, it can be secured by tightening the nut 70.

60 In operation a wheel 47 is selected having a width such that it can enter all of the depressions in the cutter and follow all of the grooves of the contour, and a former stud 67 is selected having the same width as the 65 wheel. For a left-hand cutter such as is

shown in Fig. 5, the grinding wheel is adjusted vertically so that its axis lies a suitable distance a below the axis of the cutter, this being effected by means of the screw 40 and the nut 41. Preferably there is a mark 70^a on the slide coöoperating with a scale 70^b on the bracket 37 for indicating the extent of vertical movement. This adjustment permits the wheel to cut deeper behind the cutting face of each tooth than at the cutting 75 face, thus providing the necessary relief. For a right-hand cutter the wheel is adjusted so that its axis occupies a corresponding position above the axis of the cutter. Initially, the grinding wheel is positioned with 80 its plane of rotation at right angles to the cutter axis and is held in this position by means of the rod 48. The cutter to be ground is put in place in the way shown. If the cutter has an integral shank the arbor 85 is dispensed with and the shank is inserted directly into the spindle 13. A former 62 is selected which corresponds in contour to the contour of the cutter to be ground, and this former is clamped in place by means of 90 the plate 64 and the screw 65. By means of the hand wheel 26 and the slide 25 the cutter is adjusted axially so as to bring it into proper relationship with the former. To bring the cutter and the wheel into 95 operative engagement with each other after the preliminary adjustments have been made, the slide 22 is moved by means of the hand wheel 23. When several cutters of the same kind are to be ground the diameters 100 can be kept uniform by seeing to it that the slide is brought to the same position for each cutter. This can be determined by means of the graduations on the hand wheel.

If necessary the right-hand end of the 105 arbor B can be supported by the tailstock or outboard bearing which is adjusted into alinement. This is done first by moving the slide 35 and locking and then by moving the bracket 33 relatively to the slide and clamping it by means of the bolt 36.

The operator then moves the wheel longitudinally of the cutter at the same time pressing inward to cause the former stud 67 to follow the contour of the former 62. If 115 necessary, the wheel is moved along the cutter several times until grinding of the tooth is completed. Then the cutter is indexed, use being made of the stop 17 to insure the rotation of the successive teeth to the same 120 position. It will be understood that for right-hand cutters the stop can be adjusted to engage the faces of the teeth from beneath as indicated in Fig. 9.

The grinding of the cutters in the way 125 thus far described, is satisfactory when there are no sudden variations in diameter; but when there are deep recesses or other irregularities which cause the contour to be sharply inclined toward or away from the axis, the 130

simple grinding operation set forth does not provide the amount of relief which is desirable for effecting cutting. When the wheel lies at right angles to the cutter axis 5 the relief is entirely radial, and at points where the contour of the teeth is nearly radial the amount of relief is very small. In accordance with my present invention, I provide means whereby satisfactory relief 10 can be provided for cutters having sudden variations in diameter.

In the grinding of such a cutter the teeth are first ground in the way already described, with the grinding wheel set at right 15 angles to the cutter axis. Then the wheel is drawn back from the cutter and is adjusted to an angular position such as indicated in Fig. 7, and the cutter is adjusted axially to compensate for the incidental axial movement 20 of the wheel which has taken place. After this has been done the wheel is passed over the cutter teeth as before, serving to relieve those parts which are sharply inclined and which are exposed toward the right. It 25 will be clear that the angular position of the wheel enables it to grind a non-radial relief which could not be effected with the wheel in perpendicular position.

Next the wheel is withdrawn and adjusted 30 to a position such as shown in Fig. 8 and the cutter is again adjusted axially to compensate for the incidental axial movement of the wheel. The wheel is again passed over the teeth of the cutter, serving to relieve 35 those parts which are sharply inclined and which are exposed toward the left. It will be noted that the axis of adjustment of the wheel is substantially in alignment with the former stud 67. Therefore the stud is not 40 bodily moved during adjustment and the limits of travel of the plate 10 and attached parts remain unchanged.

In order that the cutter may be accurately ground in conformity with the contour of 45 the former, it is necessary for the edge of the wheel to be accurately trued. For properly truing the wheel from time to time, I provide a wheel dressing mechanism which is preferably mounted on the machine. The 50 complete wheel dressing mechanism is shown in Figs. 10, 11 and 12, this being largely omitted from Figs. 1, 2 and 3. When the machine is in normal operation for grinding, the wheel dressing mechanism is thrown back 55 to an inoperative position as shown by dotted lines in Fig. 10.

Extending upward from the plate 12 is a bracket 73 to which is hinged the arm or frame 74 of the dressing mechanism. The 60 arm 74 is mounted on a pin 75 which extends through two lugs on the bracket 73, and the pin is provided with an enlarged head 76 adapted to engage one side of the arm 74. Threaded upon the opposite end of 65 the pin 75 is a nut or knob 77 which can be

turned to draw the head 76 against the arm and thus securely clamp the arm in position.

The outer lower end of the arm 74 is provided with a horizontal guideway in which is mounted a slide 78 horizontally movable 70 under the control of a screw 79 and a nut 80. Near its rear end the slide 78 is provided with an aperture adapted to receive the reduced end 81 of the aforesaid bolt 69. The part 81 is provided with an annular groove 75 having an inclined wall which is adapted to be engaged by a set screw 82 extending through the slide 78. By tightening the set screw the arm 74 can be securely locked to the bolt 69 and in this way connected with the plate 10 which carries the grinding wheel. In order that the plate 10 and the arm 74 may be rigidly held against any accidental play or lost motion, I prefer to provide means for locking the bar 53 against 80 movement. As illustrated, this means consists of a set screw 83 adapted to engage the bar. When the set screw is thus engaged the bar is prevented from movement and serves to prevent any transverse movement 90 of the plate 10 or of the arm 74. The clamping of the arm 74 to the bracket 73 by means of the pin 75 and the nut 77, as already described, also assists in preventing such transverse movement. The engagement of the 95 slide 78 with the pin 69 prevents any forward or backward movement of the plate 10 or of the grinding wheel and serves to hold these parts in a forward position with the former pin 67 out of engagement with the 100 former 62.

The arm 74 is provided with a vertical guideway in which is mounted a slide 84 vertically movable under the control of a screw 85 and a nut 86. The slide 84 is provided with a longitudinal horizontal aperture in which is mounted a sleeve 87 provided with an enlarged collar 88 by means of which it may be manually turned. The sleeve 87 can be clamped in any position of adjustment by means of a clamping screw 89. The sleeve 87 is provided with an eccentric aperture in which is rotatably mounted a shaft 90. Connected to or formed integrally with the shaft 90 at its rear end is an offset arm 91 provided with an aperture the axis of which is perpendicular to and in the plane of the axis of the shaft 90. In this aperture is mounted a dressing tool 92, preferably provided with a diamond point. The tool can be held in 110 place by means of a set screw 93 extended through an elongated boss 94. At the front end of the shaft 90 there is connected a hand lever 95 by means of which the shaft together with the arm 91 and the dressing tool 92 can be turned. Connected with the lever 95 is a boss 96 adapted to engage with a stop 97 and thus limit the movement of the shaft 90 to an angle of 180°. The stop 97 is preferably carried by a plate 98 which is pivoted 115

on the shaft 90 and which is held in adjusted position by means of the nut 99 on a screw extending from the slide 84.

The dressing tool must be adjusted to bring its point at the desired distance from the axis of the shaft 90, this distance being, of course, one-half the thickness of the wheel. In order that the dressing tool may be quickly and accurately adjusted, I provide gages of which one is shown at 100 in Fig. 14. The gage can be more conveniently used when the wheel dressing mechanism is in an inoperative position. In Fig. 14 I have illustrated it as swung all the way back. The gage 100 consists of a block having a central aperture adapted to receive the aforesaid boss 94. Projecting from the block are pins 101, 102 of different diameters, so located that their axes can be made to coincide with the axis of the shaft 90. A gage is selected having a pin such as 101 corresponding in diameter to the thickness of the wheel. This gage is put in place, as illustrated, and then the dressing tool 92 is adjusted into contact with the surface of the pin. After this adjustment the tool is clamped in place by means of the set screw 93 and the gage is removed.

Fig. 5, as has already been stated, shows the relative adjustment of the grinding wheel and of the cutter when the cutter is provided with radial cutting faces. Frequently, however, the cutter is provided with cutting faces which are inclined backward, with respect to the radii, as shown in Fig. 6, such cutters being commonly known as shovel tooth cutters. In the case of such cutters it is necessary to offset the grinding wheel not only through the distance a to provide the desired relief, but also through the supplemental distance b corresponding to the distance between the plane of the tool and the parallel radial plane.

As has been fully set forth in my aforesaid copending application, this offset of the wheel through the distance a causes it to engage the edge of each tooth at a plane which is parallel to but separated from the axis. And in order that the cutter may be properly ground without distortion the wheel must be trued at a plane which is at the same distance from the axis.

In order to effect relative adjustment between the grinding wheel 47 and the dressing tool 92, use is made of the aforesaid movable slide 78. It will be seen that when this slide is moved toward the rear it carries the grinding wheel with it, thus moving the axis of the wheel to a position at a distance a from the plane of action of the dressing tool. Preferably there is a scale 103 for indicating the extent of movement of the slide.

These adjustments having been made, the dressing tool is brought into engagement with the wheel by moving the slide 84 by

means of the screw 85 and the nut 86. The shaft 90 is rocked slowly back and forth by means of the lever 95, thus swinging the tool 92 in a half-circle and giving the wheel a semi-circular sectional contour in the plane 70 of movement of the tool.

It frequently happens that the diamond point of the dressing tool 92 is somewhat eccentric so that the limits of movement of the tool must be changed as illustrated in Fig. 15. This is effected by loosening the plate 98 and swinging it to one side or the other to thus move the stop 97.

Obviously the axis of the shaft 90 must pass through the central plane of the grinding wheel. However, the position of the grinding wheel will change from time to time, particularly when its bearings wear and have to be taken up. In order to adjust the shaft 90 to bring its axis into exact coincidence with the central plane of the wheel, use is made of the aforesaid eccentric sleeve 87. The clamping screw 89 is loosened as is also the nut 99 which holds the plate 98. Then the sleeve is free to be turned by means of the collar 88 and the shaft 90 can be bodily moved until it is brought into coincidence with the central plane of the wheel. Then the clamping screw 89 is tightened and also the nut 99, the plate 98 with the stop 97 having been first properly adjusted, as before stated.

I do not herein claim as part of my present invention the structural details of the wheel dressing mechanism, as these form the subject matter of my copending application for wheel dressing mechanism, Serial No. 247,636 filed on even date herewith. I do, however, claim as part of my present invention, the herein described tool dressing means combined with the other parts of the machine as set forth in the claims.

What I claim is:

1. The combination of means for supporting a toothed milling cutter having a formed contour, a grinding wheel adapted to engage the face of a tooth of the cutter, and means for supporting and guiding the grinding wheel to cause it to follow the said formed contour and to cut a relief which is non-radial at points where the face of the tooth is inclined with respect to the axis.

2. The combination of means for supporting a toothed milling cutter having a formed contour, a grinding wheel adapted to engage the face of a tooth of the cutter, and means for supporting and guiding the grinding wheel to cause it to follow the said formed contour and to cut a relief which is inclined from the radial in one direction or the other in accordance with the inclination of the face of the tooth with respect to the axis.

3. The combination of a grinding wheel rotatable about a horizontal axis and bodily

movable horizontally in any direction, means for supporting the grinding wheel and for holding it in parallelism while being moved, and means whereby the wheel 5 may be adjusted on the supporting means about a vertical axis.

4. The combination of means for supporting a toothed cutter, a grinding wheel rotatable about a horizontal axis and bodily 10 movable horizontally along the face of a tooth of the cutter, means for supporting the grinding wheel and for holding it in parallelism while being moved, and means whereby the wheel 15 may be adjusted on the supporting means about an axis intersecting the planes of parallel movement.

5. The combination of means for supporting a toothed cutter, a grinding wheel rotatable about a horizontal axis and bodily 20 movable horizontally, means for supporting the grinding wheel and for holding it in parallelism while being moved, means whereby the wheel 25 may be adjusted on the supporting means about an axis intersecting the planes of parallel movement, and a former and former stud for guiding the wheel in a fixed path along the face of a tooth of the cutter.

6. The combination of means for supporting a toothed cutter, a grinding wheel rotatable about a horizontal axis and bodily 30 movable horizontally, means for supporting the grinding wheel and for holding it in parallelism while being moved, means whereby the wheel 35 may be adjusted on the supporting means about an axis intersecting the planes of parallel movement, a relatively fixed former, and former stud on the wheel support coöperating with the former for 40 guiding the wheel in a fixed path along the face of a tooth of the cutter, the axis of the stud being substantially in alinement with the axis of adjustment of the wheel.

7. The combination of means for horizontally 45 supporting a toothed cutter, a grinding wheel rotatable about a horizontal axis and bodily movable horizontally along the face of a tooth of the cutter, means for supporting the grinding wheel and for holding it in 50 parallelism while being moved, the wheel being located with its axis vertically offset from the plane of the front edge of the tooth of the cutter, and means whereby the wheel 55 may be adjusted on the supporting means about a vertical axis.

8. The combination of means for horizontally 60 supporting a toothed cutter, a grinding wheel rotatable about a horizontal axis and bodily movable horizontally along the face of a tooth of the cutter, means for supporting the grinding wheel and for holding it in parallelism while being moved, means for adjusting the wheel vertically to cause its axis to be vertically off-set to any desired extent from the plane of the front 65

edge of the tooth of the cutter, and means whereby the wheel may be adjusted on the supporting means about a vertical axis.

9. The combination of means for supporting a toothed cutter, a grinding wheel 70 bodily movable along the face of a tooth of the cutter, a support for the grinding wheel, pantographic mechanism for holding the wheel support in parallelism while being moved, and means whereby the wheel may 75 be adjusted on the support about an axis intersecting the planes of parallel movement.

10. The combination of a grinding wheel 80 bodily movable horizontally in any direction, means including a bracket for supporting the grinding wheel and for holding it in parallelism while being moved, means whereby the wheel and the bracket may be adjusted on the supporting means about a vertical axis, a link pivoted to the support, 85 and a clamp on the bracket for engaging the link to hold the wheel in any position of adjustment.

11. The combination of means for rotatably supporting a toothed milling cutter, a 90 grinding wheel adapted to engage and move along the face of a tooth of the cutter, a finger adapted to engage the front of a cutter tooth to determine its position, and an adjustably jointed holder for the finger. 95

12. The combination of means for rotatably supporting a toothed milling cutter, a grinding wheel adapted to engage and move along the face of a tooth of the cutter, a 100 finger adapted to engage the front of a cutter tooth to determine its position, and a holder for the finger universally adjustable to permit the finger to engage a tooth either at the top or at the bottom.

13. The combination of a holder for a milling cutter adapted to permit the cutter to be turned about its axis, a bodily movable grinding wheel having its axis substantially parallel to the cutter axis, means for holding the wheel in parallelism while being 110 moved, a former and former stud one fixed and the other movable for guiding the wheel in a fixed path along the surface of the cutter, means for effecting relative adjustment between the cutter holder and the former longitudinally of the cutter axis whereby the position of the cutter and the path of movement of the wheel are properly correlated, and adjustable stops for limiting the said longitudinal movement. 115

14. The combination of means for supporting a toothed cutter, a bodily movable grinding wheel, means for supporting the grinding wheel and for holding it in parallelism while being moved, and means for 120 moving the cutter support transversely comprising a slideable rack bar, a link connecting the bar with the support, a pinion engaging the rack and a hand lever for turning the pinion. 130

15. The combination of means for supporting a toothed cutter, a bodily movable grinding wheel, means for supporting the grinding wheel and for holding it in parallelism while being moved, and means for moving the cutter support transversely comprising a slidable rack bar, a link connecting the bar with the support, a pinion movable into or out of engagement with the rack 10 and a hand lever for turning the pinion.

16. The combination of a main frame, means on the main frame for supporting a cutter in fixed position, a grinding wheel movable along the face of the cutter, means 15 for supporting the grinding wheel and for holding it in parallelism while being moved, a wheel dressing mechanism pivoted to the main frame and movable to or from an operative position, means for connecting the 20 grinding wheel support to the dressing mechanism when the latter is in operative position thus holding the grinding wheel in position to be dressed, and means supplemental to the dressing mechanism for locking the support against transverse movements.

25. 17. The combination of a main frame, means on the main frame for supporting a

cutter in fixed position, a grinding wheel movable along the face of the cutter, means 30 for supporting the grinding wheel and for holding it in parallelism while being moved, a wheel dressing mechanism pivoted to the main frame and movable to or from an operative position, means for connecting the 35 grinding wheel support to the dressing mechanism when the latter is in operative position thus holding the grinding wheel in position to be dressed, and means for rigidly clamping the dressing mechanism to the 40 main frame when it is connected to the wheel support.

18. The combination of a main frame, means on the main frame for supporting a contour milling cutter in fixed position, a 45 grinding wheel movable along the face of the cutter, means for supporting the grinding wheel and for holding it in parallelism while being moved, and a former and a former stud for guiding the wheel in a fixed 50 path, the former consisting of a main part and a detachable auxiliary part having the required contour.

In testimony whereof, I hereto affix my signature.

BENGT M. W. HANSON.
